UNITED STATES PATENT OFFICE.

GEORGE W. MILLS AND JAMES E. SIMPSON, OF GEORGETOWN, PENNSYLVANIA.

GRAVITY CONCRETE-MIXER.

1,072,143.

Specification of Letters Patent.

Patented Sept. 2, 1913.

Application filed November 15, 1912. Serial No. 731,469.

To all whom it may concern:

Be it known that we, GEORGE W. MILLS and JAMES E. SIMPSON, citizens of the United States, and residents of Georgetown, 5 in the county of Beaver and State of Pennsylvania, have invented a new and useful Improvement in Gravity Concrete-Mixers, of which the following is a specification.

Our invention is an improvement in gravity concrete mixers, and has for its object the provision of mechanism of the character specified, by means of which the elements necessary for the formation of concrete may be intimately combined in proper proportions by the mere act of passing the materials through the device by gravity.

In the drawings:—Figure 1 is a transverse vertical section of the improvement, Figs. 2 and 3 are sections on the lines 2—2 20 and 3—3 respectively of Fig. 1, Fig. 4 is a plan view of one of the mixing devices, and Fig. 5 is a side view of the mixing device partly in section.

The present embodiment of the invention 25 comprises a plurality of superposed hoppers, the upper hopper 1 having its outlet 2 above and in line with the outlet 3 of the lower hopper 4. A suitable framework 5 is provided for supporting the hoppers, and 30 a platform 6 is arranged on the top of the framework. An opening 7 is provided in the platform, and brackets 8 are arranged at the opening for engagement by the hopper. The outlet 2 of the hopper is below 35 the platform, and the lower hopper 4 is supported by brackets 9, similar to the brackets 8, the said brackets 9 being arranged on cross bars 10 of the framework. The top of the upper hopper is directly below an opening 11 in a suitable container 12 for the raw material, the opening 11 permitting the 40 material to be fed into the upper hopper which is a receiver for the different elements of the combination.

45 A framework consisting of crossed pairs of plates 13 and 14 is arranged in the upper hopper, each of the said plates being approximately triangular in shape and arranged with its base upward. The bases 50 of the plates are in the same plane, and the arrangement of the plates provide for nine sub-divisions or compartments in the framework. The arms 15 of a yoke are secured to the framework at the central compartment 55 16, and the body 17 of the yoke has connected therewith one end of a lever 18,

pivoted intermediate its ends at 19 to the lower end of a link 20, whose upper end is pivoted at 21 to the receptacle or container for the raw material. The body 17 of the 60 yoke is provided with a vertical opening through which is movable a rod 22, and the upper end of the rod 22 is engaged with a block 23, having oppositely arranged bearing lugs or journal pins not shown, which 65 engage with slots 24 in one end of a lever 25, pivoted at 26 to the lower end of a link 27, whose upper end is pivoted at 28 to the receptacle, before mentioned. The rod 22 is 70 slidable through the block 23, and downward movement of the rod is limited by a pin 29, passing through the upper end of the rod above the block.

The outlet 2 of the upper hopper is provided with oppositely arranged lugs 30, and 75 a rod 31 depends from each of the said lugs. A mixer or baffle plate 32 is supported by the rods 31, the said mixer or baffle plate being of frusto-conical form, and hollow as shown. The said mixer or baffle plate is in 80 fact a hollow cone having its apex cut away and provided with bearings 33 at opposite sides, through which are passed the lower ends of the rods 31 and cotter pins 34 or the like are passed through the lower ends 85 of the rods to support the device.

A conical gate 35 is secured to the lower end of the rod 22, the said gate fitting within the mixer or baffle plate and closing the upper end thereof as shown in dotted lines 90 in Fig. 1. When the rod 22 is lifted by swinging the lever 25, the gate 35 is first lifted to close the opening 36 at the top of the mixer or baffle plate, and a further movement of the rod lifts both gate and 95 mixer into the dotted line position of Fig. 1, thus closing the outlet of the upper hopper. The framework 13—14 may be lifted by means of the lever 18, and normally the 100 said framework occupies the position shown in Fig. 1.

In the operation of the construction described the hopper 1 with its outlet closed is first provided with a layer 37 of gravel, the said layer being arranged on the inner 105 surface of the hopper of the required depth, and the framework 13—14 is placed as shown in the said Fig. 1. The framework 13—14 as before stated, provides for nine compartments, the central compartment 16 110 being left empty to permit the free movement of the rod 22. The compartments in

line with the central compartment, four in number, are adapted to receive sand, while the diagonal compartments are adapted to receive cement. When the hopper has been loaded as above specified, with the layer of gravel at the outside and the sand and cement in the compartments of the framework, the framework may be lifted by means of the levers 18, thus leaving all of the ingredients in the position shown, but in contact with each other instead of being separated by the partitions or plates 13—14.

The outlet 3 of the lower hopper is normally closed by a door or gate 38, pivoted to a threaded lug 39 extending downwardly from a bearing ring 40, encircling the outlet, the gate having a bearing boss 41 for engaging the lug. A nut 42 holds the gate on the lug and a cotter pin or the like may be passed through the lug to lock the nut in place. A handle 43 is provided for manipulating the gate, and the said gate at the opposite end from the handle rests upon a holding lug 44, connected with the bearing ring.

A mixer or baffle plate 45 of frusto-conical form is supported coaxially with the hopper 4, by means of bracket arms 46, extending outwardly from the top of the baffle plate and connected to the inner face of the hopper. The open lower end 47 of the baffle plate is in alinement with the outlet 3 of the hopper, and the top opening of the baffle plate is below the outlet of the upper hopper. A plurality of deflecting plates 48 are arranged at the upper end of the baffle plate in spaced relation on the inner face thereof, each plate having one of its edges turned over as shown at 49. The arrangement is such that when the material falling from the outlet strikes the said plates, the said material will mount the turned over edge 49 of the plates, and a portion thereof will be thrown on top of the remaining portion. The said plates will in effect turn over and thoroughly mix the material. Similar plates 50 are arranged on the outer surface of the mixer 32 near the lower edge thereof, each plate having one of its edges turned over as shown in Fig. 1 in the same manner as the plates 48.

The mixers or baffles 32 and 45 are of substantially the same construction and operate in the same manner, the said plates being however, oppositely arranged. The upper baffle plate or mixer 32 is arranged with its small end upward to deflect a portion of the material outward, while the baffle plate or mixer 45 is arranged with its large end upward to deflect a portion of the material inward. The operation is the same, and they are arranged as specified in order to thoroughly mix the material.

In operation, after the raw materials, have been arranged in the upper hopper as

specified, the lever 25 is operated to place the cone 32 and the gate 35 in the position shown in full lines in Fig. 1. The materials in the upper hopper will now rush out through the outlet, a portion striking the upper surface of the cone, while another portion will pass through the opening 36 at the top of the cone and will strike the outer surface of the gate. That portion of the material that strikes the outer surface thereof will be thrown outwardly, and as it passes down it will strike the plates 50 and the turned over edges 51 thereof, and will be thoroughly mixed as it leaves the cone. This portion will then strike the baffle plate 45 at the upper edge thereof, and will be again turned over and intimately mixed by the deflecting plates 48. A portion of the material will be thrown outside the baffle plate, striking the inner surface of the hopper 4, and another portion will pass down through inside the mixing device, so that all the materials will be very intimately and thoroughly mixed before passing out at the outlet 3 of the lower hopper. The deflected plates 48 and 50 will impart a whirling or eddying movement to the materials, and when the materials finally settle in the hopper 4, they will have been thoroughly mixed and in condition for use.

In Fig. 1 mechanism is shown for spraying water on to the materials after they are mixed. The said mechanism is so arranged that every portion of the material is subjected to the action of the spray. A water pipe 52 is lead from a suitable source of supply to a point above the hopper, and a valve 53 is interposed in the said pipe adjacent to the position occupied by the operator when operating the device. A vertical section of pipe 54 is connected with the inner end of the pipe 52, and the said vertical section passes through a bearing 55 on one of the arms 15 of the yoke, the said section being slidable through the bearing. A ring 56 is arranged at the lower end of the pipe 54, the said ring having a plurality of series of openings in its bottom for throwing the water inwardly and outwardly, to thoroughly spray all of the material as it passes through the outlet. The pipe does not interfere with the movement of the framework.

We claim:

1. In a gravity concrete mixer, a mixing device comprising a frusto conical member having a plurality of mixing plates near its large end, each of the said plates having one of its edges turned over on the plate in spaced relation, said plates being similarly arranged and in spaced relation, and means for feeding the material to be mixed axially of the frusto conical member.

2. In a gravity concrete mixer, a mixing device comprising a frusto conical member

having a plurality of mixing plates near its large end, each of the said plates having one of its edges turned over on the plate in spaced relation, and means for feeding the material axially of the frusto conical member.

3. In a gravity concrete mixer, a mixing device comprising a frusto conical member having a plurality of mixing plates near its 10 large end, each of the said plates having one of its edges turned over on the plate in spaced relation.

4. In a gravity concrete mixer, a baffle plate provided with a plurality of mixing 15 plates, each plate having one of its edges turned over upon the plate in spaced relation.

5. In a gravity concrete mixer, a hopper provided at its outlet with oppositely arranged 20 depending rods, a frusto-conical baffle plate mounted to slide on the rods and arranged with its small end upward, means within the baffle plate for raising and lowering said plate to open or close the outlet

of the hopper, and a plurality of mixing 25 devices arranged around the upper edge of the baffle plate, each plate having one of its edges bent over upon the edge of the plate in spaced relation.

6. In a gravity concrete mixer, a plurality 30 of oppositely arranged frusto-conical baffle plates, each having a plurality of mixing plates near one edge, each of the said mixing plates having one of its edges turned over upon the baffle plate in spaced relation, the 35 mixing plates on each baffle plate being similarly arranged.

7. In a gravity concrete mixer, a plurality 40 of oppositely arranged frusto-conical baffle plates, each having a plurality of mixing plates near one edge, each of the said mixing plates having one of its edges turned over upon the baffle plate in spaced relation.
